HEINRICH DERSEN, OF ST. TONIS, GERMANY, ASSIGNOR TO THE FIRM MASCHINEN-FABRIK CARL ZANGS AKTIENGESELLSCHAFT, OF KREFELD, GERMANY

DRIVE FOR DOBBY AND JACQUARD LOOMS

Application filed June 7, 1928, Serial No. 283,631, and in Germany May 3, 1927.

This invention relates to a drive for doby and Jacquard looms.

The connection between the loom and the doby or jacquard machine has hitherto been established by the aid of one or more connecting rods, connected with cranks or eccentrics. Since this method of driving is not suitable for rather high speeds of revolution, a transition has been made to driving by means

10 of a chain or a vertical revolving shaft.

All these means of driving the shedding machine are complicated and subject to a great deal of wear. The transmission of the movement from the loom to the shedding machine was always inaccurate since the shedding machine has to follow the movements of the loom in point of time. Furthermore these transmission elements required a great deal of space, and formed a source of 15 danger to the persons attending to the machines, since they were located outside the loom itself.

The present invention obviates these disadvantages and provides a new means for transmitting motion from the loom to the shedding machine. Instead of the rigid machine elements hitherto employed, the present invention utilizes a column of liquid, such as is frequently employed in power-transmission 20 machinery.

The invention is illustrated by way of example in one constructional form in the accompanying drawings, wherein

Fig. 1 shows a loom with a jacquard machine in side elevation, and

Fig. 2 shows the same apparatus in front elevation.

The method of operation of this apparatus is as follows:—In a stationary cylinder *a* there moves a piston *b*, which is connected with an eccentric *c* of the loom by a lever *d*. By means of a pipe *e*, connection is established with a cylinder *f*, which is likewise stationary. In this cylinder there moves a 45 piston *g*, which is connected by connecting-

rod gear with the doby or jacquard machine. The piping and the cylinder are filled with liquid, such as machine oil for example. Since oil is practically incompressible, the doby or jacquard machine, connected with 50 the loom shaft *s* by the oscillating column of oil, must follow the movements thereof in point of time.

What I claim is:—

1. Driving means for communicating motion from looms to doby and jacquard shedding machines, comprising a stationary cylinder on said loom, a piston capable of reciprocating in the cylinder, means for reciprocating said piston in synchronism with the 55 reciprocating movements of the loom, a stationary cylinder on the shedding machine, a second piston adapted to reciprocate in said second cylinder, and a pipe adapted to contain a liquid, said pipe connecting the two 60 cylinders with one another in such a manner that said liquid communicates reciprocating movements from the loom piston to the shedding-machine piston.

2. Driving means for communicating motion from looms to doby and jacquard machines, comprising a stationary cylinder on said loom, a piston capable of reciprocating in the cylinder, an eccentric on the loom, a lever adapted to communicate reciprocating 70 movements to the piston from the eccentric, a stationary cylinder on the shedding machine, a second piston adapted to reciprocate in said second cylinder, and a pipe adapted to contain a liquid, said pipe connecting the two 75 cylinders with one another in such a manner that said liquid communicates reciprocating movements from the loom piston to the shedding-machine piston, and a connecting rod adapted to communicate reciprocating movements from the second piston to the shedding machine.

3. Driving means for communicating motion in Jacquard looms, comprising a shedding mechanism, a main driving shaft for 85

90

the loom, a hydraulic actuating device operatively connected to said shaft so as to be capable of actuation by the shaft, a hydraulic actuating device operatively connected to
5 said shedding mechanism so as to be capable of driving the shedding mechanism and a pipe connected to said hydraulic actuating devices and adapted to contain a liquid for transmitting power from said first-mentioned
10 actuating device to said second-mentioned actuating device, for the purpose of transmitting motion from said shaft to said shedding mechanism.

In testimony whereof I have signed my
15 name to this specification.

HEINRICH DERSEN.
